STEAM BOILER

David S. Jacobus, Montclair, N. J., and Robert K. Behr, Mount Vernon, N. Y., assignors to The Babcock & Wilcox Company, Newark, N. J., a corporation of New Jersey

Application December 1, 1932, Serial No. 645,162

25 Claims. (Cl. 122—299)

The present invention relates to the construction and operation of water tube steam boilers, and particularly to boilers of that type which are characterized by the arrangement of fluid heating surface in the space above a main bank of steam generating tubes and between the circulation tubes which provide a natural fluid circulation between that bank and an elevated steam and water drum and aid in defining the front and rear walls of the portion of the boiler above the main steam generating tube bank. The invention is especially applicable to the construction of water tube boilers in which the steam and water drum is located at a substantial distance above the uppermost point of steam generation in the main tube bank, whereby a rapid natural circulation of the fluid through the tube bank is maintained by the high hydraulic head to which it is subjected.

The general object of our invention is the provision of a water tube steam boiler of the general character described which is further characterized by its relatively low cost of construction, economy of maintenance and operation, relatively high steaming capacity, and small amount of floor space required. A further and more specific object is the provision of a high drum water tube boiler with an improved construction and arrangement therein of the fluid heating surface supplemental or auxiliary to the natural circulation steam generating bank by which high rates of heat transference to the supplemental surface are maintained, tube replacement is facilitated, tubes of relatively short horizontal extent may be used, and an effective arrangement for supporting the tubes provided.

The various features of novelty which characterize our invention are pointed out with particularity in the claims annexed to and forming a part of this specification. For a better understanding of the invention, its operating advantages and specific objects attained by its use, reference should be had to the accompanying drawings and descriptive matter in which we have illustrated and described preferred embodiments of our invention.

Of the drawings:

Fig. 1 is a somewhat diagrammatic sectional elevation of a water tube steam boiler constructed in accordance with our invention, certain parts being omitted for purposes of clarity;

Fig. 2 is a detail on an enlarged scale of a portion of the boiler shown in Fig. 1;

Fig. 3 is a section on the line 3—3 of Fig. 2;

Fig. 4 is a view on an enlarged scale of a tube connection shown in Fig. 1;

Fig. 5 is a view similar to Fig. 1 of a modification; and

Fig. 6 is a view similar to Fig. 1 of a second modification.

In the steam boiler illustrated in Figs. 1 to 4 of the drawings, 10 designates a combustion chamber formed by walls 11 provided with cooling tubes 12 covered by blocks and connected into the boiler circulation as hereinafter described. Powdered fuel is supplied to the combustion chamber through fuel burners 13 in one of the walls thereof along with preheated air for combustion. The air is preheated in an air heater 14 and delivered through a duct 15 having branches 16 leading to a chamber 17 surrounding the fuel burners. Dampers 18 control the supplies of air to the chamber 17.

The high temperature heating gases pass upwardly from the combustion chamber 10 into contact with fluid heating surface arranged as hereinafter described. Most of the solids carried by the heating gases are separated out by rows of horizontally spaced furnace slag screen or dust collecting tubes 20 extending across the upper part of the combustion chamber. The tubes 20 have their ends connected to external headers 21 and 22 and are provided with a refractory covering. In operation, the tubes 20 will ordinarily have a coating of molten slag which aids in collecting the solid particles. The headers 21 and 22 are connected into the boiler circulation by tubes 23 and 24 respectively.

Extending across the upper end of the combustion chamber is a bank of horizontally inclined tubes 25, the lower rows of which are further spaced apart vertically and/or horizontally than the upper rows to form a boiler slag screen. The tubes 25 are arranged in side-by-side sections 40 and their ends are connected to corresponding downtake and uptake headers 26 and 27 respectively. A rapid natural circulation of the heated fluid is maintained through the tube bank 25 by the arrangement of a horizontal transverse steam and water drum 28 suspended at a substantial distance above the highest point of steam generation in the tube bank 25 and by downtake and uptake circulator tubes 29 and 30 connecting the drum 28 to the downtake and uptake headers 50 respectively. The circulators 29 and 30 extend vertically from the headers, and in conjunction with refractory material 31, form fluid cooled walls defining the rear and front walls respectively, of the portion of the boiler above the tube 55

bank 25. Horizontal portions 30^a of the uptake circulators define the roof of the boiler. The uptake circulators 30 are supported from above by suitable rods 30^b welded to the upper ends of 5 their vertical portions, while the downtake circulators are carried by the drum 28. The combustion chamber wall tubes 12 are connected to the drum 28 by riser tubes 32 arranged at the outer sides of the boiler wall portions heretofore 10 mentioned.

With the boiler constructed as described, a gas-tight space of substantial height and volume is available above the tube bank 25 and between the uptake and downtake circulators, in which most, 15 if not all, of the supplemental or auxiliary fluid heating surface of the boiler may advantageously be located. In accordance with our invention a high mass flow of heating gases past the heating surface without decreasing the permissible latitude in tube spacing is obtained as well as other advantages hereinafter pointed out by dividing the space above the tube bank and between the circulator rows into successive upflow and downflow gas passages 40 and 41 connected for a series 20 flow of heating gases therethrough. As shown in Figs. 1, 2 and 3, the gas passages are formed by a partition 33 extending inwardly and upwardly from the rear wall of the boiler and terminating at a level below the bottom of the drum 28. The 25 partition is formed by refractory blocks 33^a backed by plates 33^b having their flanged edge portions connected. The partition is cooled and supported in its desired position by one or more rows of steam generating tubes 25^a extending from the 30 uppermost rows of tube openings in the downtake headers upwardly along the inner face of the partition, and having their upper ends connected to an intermediate header 34 horizontally arranged in the vertical portion of the partition 33. 35 The tubes 25^a are advantageously connected into the boiler circulation by a lesser number of tubes 35 extending between and spaced along the header 34 and drum 28. The partition is suspended from the external frame-work by rods 38 40 welded to the bent portions of the tubes 35.

Thus the heating gases from the combustion chamber will first pass over the tube bank 25 and then upwardly through the gas passage 40, over the upper end of the partition 33 and across the 45 tubes 35, and then downwardly through the gas passage 41. As shown in Figs. 1 and 2, alternate downtake circulators are bent laterally to increase the gas flow area between adjacent tubes, and the wall-forming refractory material 31 associated 50 with the inner row of downtake circulators terminates at a level corresponding to the lower end of the vertical portion of the partition 33, to form a gas outlet 42. The outlet 42 is connected to the 55 heating gas flow passages of the air heater 14 and the gases after passing therethrough are discharged to a stack connection 44.

The supplemental or auxiliary fluid heating surface of the boiler is divided into a steam superheating section and a water heating section, and 60 the respective sections arranged so as to be subjected to the most desirable heat transfer conditions. As shown in Fig. 1, the steam superheating section is located in the first upflow gas passage and divided into upper and lower units or 65 sections 45 and 46 respectively, each comprising a bank of vertically looped side-by-side tubes with horizontal leg portions of relatively short length arranged in parallel vertical planes transverse to the planes in which the circulator and 70 partition-supporting tubes are located. Adjoin- 75

ing leg portions in each bank are preferably connected in any suitable manner to form a unitary structure which is supported from the uptake circulators 30 and partition supporting tubes 35 by lugs 47 on the looped portions of the superheater tubes. The ends of the looped tubes of the upper superheater section are connected to inlet and outlet headers 49 and 50 respectively, while the tubes of the lower section are connected to inlet and outlet headers 51 and 52 respectively. Steam 10 supply tubes 53 connect the drum 28 to the inlet header 51 of the lower section. The outlet header 52 is connected to a pipe 54 leading to a suitable regulable steam desuperheater 55, which may be of the character illustrated in the copending application of John E. Black, Serial No. 446,270, filed April 22, 1930, and the partly desuperheated steam is returned through a pipe 56 leading to the header 49 of the upper section. The steam at the desired degree of superheat passes from the outlet header 50 to a point of use. Headers 49, 50, 51 and 52 are supported independently of the bracket supports 47, 48, by suitable supports (not shown).

The water heating surface is advantageously located in the downflow gas passage 41 and preferably divided into upper and lower units or sections 60 and 61, each also consisting of a bank of vertically looped side-by-side tubes having horizontal leg portions of relatively short length extending across the gas passage in vertical planes 30 transverse to the planes in which the downtake circulators and partition-supporting tubes are located. Each economizer section is formed in a unitary structure and supported from the circulator and partition-supporting tubes in the same 35 manner as the superheater tubes. By this distribution of the tube load, excessive strains on the downtake connections to the drum 28 are avoided. The lower ends of the tubes in the lower economizer section are connected into a supply header 40 62, which receives a supply of feed water at the desired pressure from a suitable feed pump (not shown). The upper ends of the tubes of the upper section are directly connected into the steam and water drum 28. An upward serial flow of the 45 heated fluid is maintained between the two sections by connecting corresponding tubes in the lowermost row of the upper section to corresponding tubes in the uppermost row of the lower section. These tube connections are advantageously arranged within the space between the tube banks and are formed by threading the ends of each pair of tubes 60 and 61, as shown in Fig. 4, and connecting the threaded ends by a coupling 63. Each coupling is seal welded to the corresponding tubes as indicated at 64. The use of 50 expensive externally located return bends is thus 55 avoided.

The described arrangement of the tubes in the superheater and economizer sections permits 60 rapid replacement of any of those tubes. The tubes are withdrawn through the spaces between adjacent uptake or downtake circulators and then through openings left by removable panels in the outer casing 64 of the boiler. To expedite 65 the replacement of the economizer tubes, access doors 65 are provided in the portion of the side walls opposite the interbank space providing access to the couplings 63. These openings may also be used for access to the handhole openings in 70 the header 34 and for the insertion of steam lances or other tube cleaning equipment.

The inclined portion of the partition 33 is preferably arranged at an angle greater than the angle of repose of the solid residue which tends 75

to deposit thereon from the downflowing heating gases. This material would tend to collect in the space between the lower ends of the down-take circulators and the lower end of the partition 33 and cause corrosion of the headers and of the circulator connections thereto. To avoid the formation of a dust pocket in this portion of the boiler the partition 33 is provided with a rearward extension 66 formed by spaced plate members 67 surrounding the lower portions of the down-take circulators, the interplate space being packed with insulating material 68. With this arrangement the inclined surface of the partition is continued to a point beyond the down-take circulators. Plates 69 extend between the upper ends of the headers 26 and the partition extension 66, closing that side of the pocket.

With a steam boiler constructed as described, fuel may be burned in the combustion chamber 10 at relatively high rates of B. t. u. release, and high temperature heating gases pass upwardly across the slag screen tubes 20, by which a large portion of the solid material carried by the gases is removed. Combustion may continue in the space between the tubes 20 and tube bank 25. The heating gases pass upwardly over the entire length of the tubes 25. The mass flow of heating gases is substantially increased in the upper portion of the boiler while maintaining a desirable latitude in tube spacing and with a minimum increase in draft loss, by the division of the space above the tube bank 25 and between the circulators into several gas passages. The mass flow will progressively increase during the passage of the gases through the tapering lower portion of the first upflow passage. The arrangement of the superheating surface in the narrowest portion of the upflow gas pass with a parallel flow of the heating gases and heating fluid will afford a maximum heating effect with maximum safety from tube overheating. The steam generated in the furnace water walls and tube bank 25 and any steam that may be generated in the upper part of the economizer section 60 is delivered to the drum 28 from which it passes to the superheater inlet header 51. The degree of superheat may be accurately controlled and the metal temperatures of the superheater tubes in the upper superheater section maintained within the permissible limits by the interposition of the regulable desuperheater 55 between the headers 52 and 49. The steam after being partly desuperheated will be again raised in temperature while passing through the upper section 45. Explosion doors 70 of any suitable type are provided in the roof of the boiler to relieve any excess pressure which may develop in the furnace and passage 40 due to possible explosive combustion of the fuel.

The counterflow arrangement of the economizer in the downflow gas passage 41 is particularly advantageous. With this arrangement the heating gases will progressively decrease in temperature during their downward flow, while the temperature of the feed water will progressively increase during its upward passage through the tubes. The economizer surface is of relatively high heat absorptive capacity as compared to the superheating surface, and the substantial decrease in the heating gas temperature in the passage 41 effects a siphonal action on the heating gas circulation through the upper part of the boiler. The direction of gas flow in the passage 41 takes advantage of the natural tendency of the heating gases on cooling to flow down-

wardly. The arrangement of the economizer tubes containing the highest temperature fluid at the highest level avoids opposition to fluid flow therethrough when steam is generated in the upper section. Equalization of flow conditions in the several economizer tubes is substantially improved by their separate connections with the drum 28. The heating gases leave the downflow passage through the outlet 42, passing across the lower portions of the downtake circulators 10 to the air heater 14, in which the air for combustion is preheated by the gases flowing to the stack connection 44.

In the modification illustrated in Fig. 5, the upflow gas passage 40 contains only a single bank 16 of superheater tubes 80, the remaining portion of that passage being occupied by the first or inlet section 81 of the economizer. The second or discharge economizer section 82 is located in the downflow passage with its lower end connected to the first economizer section by tubes 83. Feed water supplied to the upper header 84 of the first economizer section flows downwardly through the tubes in the upflow gas passage and thence to the lowermost tubes in the downflow gas passage. The upper ends of the tubes in the section 82 are directly connected to the steam and water drum 28. The construction and mode of operation is otherwise similar to that heretofore described.

In the modification illustrated in Fig. 6, the space above the tube bank 25 is divided into three passages, and the heating gas outlet 90 located in the top of the boiler. The heating gas passages are formed by fluid cooled partitions 91 and 92, the partition 91 extending inwardly and upwardly from the rear wall of the boiler and cooled and supported by rows of tubes 93 and 94. The tubes 93 have their lower ends connected to the upper portion of the down-take headers and their upper ends connected to a cross header 95. The tubes 94 extend from the header 95 to a header 96 located in the top of the boiler and which in turn is connected to the steam and water drum 28 by horizontal tubes 97. The partition 92 is carried on the upper portions of tubes 98 extending vertically from the header 95 and having their upper ends connected to the drum 28. By this partition arrangement the space between the uptake and downtake circulators and above the tube bank will be divided into two upflow gas passages 100 and 101 and an intermediate downflow gas passage 102, all arranged in series. The first upflow gas passage is occupied by a steam superheater of the type heretofore described, receiving its supply of steam from the drum 28 through tubes 103. The remaining gas passages are occupied by economizer sections 104 and 105, the tubes of which extend across the width of the boiler. The economizer sections are arranged for a series flow therebetween through tubes 106. The economizer is of the counter-flow type, feed water being supplied to the upper header of the section 105 through a pipe 107 and the uppermost tubes of the section 104 directly connected to the drum 28. The boiler construction and mode of operation are otherwise similar to that shown in Fig. 1.

It will be observed that in each of the boiler constructions described, the convection heating surface is divided into separate sections containing fluids of different heat absorptive capacities and located in different zones of gas flow, with the heat absorption in each section being sub-

stantially completed before the heating gases contact with the succeeding section. The surface first contacted by the gases contains a fluid at substantially constant temperature, while the remaining surface contacted contains fluids progressively increasing in temperature and as such, advantageously located in the zones of greater mass flow, with the surface containing the fluid to be heated to the highest temperature confined to the first passage. By this serial absorption of heat by surface containing different fluids, it is possible to most economically arrange the heating surface, i. e., use a minimum amount of heating surface for a required heating effect, while obtaining maximum safety against overheating of the tubes.

While in accordance with the provisions of the statutes we have illustrated and described herein the best forms of our invention now known to us, those skilled in the art will understand that changes may be made in the form of the apparatus disclosed without departing from the spirit of the invention covered by our claims, and that certain features of our invention may sometimes be used to advantage without a corresponding use of other features.

We claim:

1. A steam boiler comprising a combustion chamber, a horizontally inclined bank of steam generating tubes arranged across the path of the heating gases leaving said combustion chamber, a horizontal transverse steam and water drum positioned a substantial distance above the uppermost point of steam generation in said tube bank, uptake and downtake circulators connecting said drum to opposite ends of said tube bank and providing a rapid natural fluid circulation between said drum and tube bank and respectively defining the front and rear walls of the upper portion of said boiler, a partition extending inwardly and upwardly from the rear wall of said boiler and dividing the space above said tube bank and between said circulators into successive upflow and downflow heating gas passages arranged in series, a row of partition-supporting tubes extending upwardly from said downtake headers in heat absorbing relation with said partition and having their upper ends connected to said drum, a bank of fluid heating tubes positioned in said upflow gas passage between said uptake circulators and said partition-supporting tubes, and a second bank of fluid heating tubes positioned in said downflow gas passage between said partition-supporting tubes and said downtake circulators, the tubes in each of said last mentioned banks having looped inner portions supported on said partition-supporting tubes.

2. A steam boiler comprising a combustion chamber, an inclined bank of steam generating tubes arranged across the path of the heating gases leaving said combustion chamber, rows of uptake and downtake headers connected to opposite ends of said tube bank, a transverse steam and water drum positioned directly above said downtake headers and a substantial distance above said tube bank, vertically arranged uptake and downtake circulators connecting said drum and headers and providing a natural fluid circulation between said drum and tube bank and respectively defining the front and rear walls of the upper portion of said boiler, a partition extending inwardly and upwardly from the rear wall of said boiler and dividing the space above

said tube bank and between said circulators into successive upflow and downflow heating gas passages arranged in series, a row of partition-supporting tubes extending upwardly from said downtake headers in heat absorbing relation with said partition and having their upper ends connected to said drum, a bank of looped fluid heating tubes positioned in said upflow gas passage, means for supporting said looped tube bank from said uptake circulators and partition-supporting tubes, a second bank of looped fluid heating tubes positioned in said downflow gas passage, and means for supporting said second looped tube bank from said partition-supporting tubes and downtake circulators. 15

3. A steam boiler comprising a combustion chamber, an inclined bank of steam generating tubes arranged across the path of the heating gases leaving said combustion chamber, uptake and downtake headers connected to opposite ends of said tube bank, a steam and water drum positioned above said tube bank, uptake and downtake circulators providing a natural fluid circulation between said drum and tube bank and respectively defining the front and rear walls of the upper portion of said boiler, a row of supporting tubes extending inwardly and upwardly from said downtake headers and having their upper ends connected to said drum, means for suspending said row of supporting tubes, fluid heating tubes positioned in the upper portion of said boiler, and means for jointly supporting said fluid heating tubes from said supporting tubes and circulators.

4. A steam boiler comprising a combustion chamber, an inclined bank of steam generating tubes arranged across the path of the heating gases leaving said combustion chamber, a horizontal steam and water drum positioned a substantial distance above the uppermost point of steam generation in said tube bank, uptake and downtake circulators providing a natural fluid circulation between said drum and tube bank and respectively defining the front and rear walls of the upper portion of said boiler, a partition extending inwardly and upwardly from the rear wall of said boiler and dividing the space above said tube bank and between said circulators into successive upflow and downflow heating gas passages, a bank of steam superheater tubes located in said upflow gas passage, means for supporting said superheater tubes from said uptake circulators, a bank of economizer tubes positioned in said downflow gas passage, and means for supporting said economizer tubes from said downtake circulators. 55

5. A steam boiler comprising a combustion chamber, a bank of horizontally inclined steam generating tubes arranged across the path of the heating gases leaving said combustion chamber, rows of uptake and downtake headers connected to opposite ends of said tube bank, a horizontal transverse steam and water drum positioned a substantial distance above the uppermost point of steam generation in said tube bank, uptake and downtake circulators connecting said drum and headers and providing a rapid natural fluid circulation between said drum and tube bank and respectively defining the front and rear walls of the upper portion of said boiler, partitions dividing the space above said tube bank and between said circulators into successive upflow and downflow heating gas passages arranged in series, rows of partition-supporting tubes in heat absorbing relation with said partitions and having 75

their upper ends connected to said drum, a bank of fluid heating tubes of relatively low heat absorptive capacity positioned in the first upflow gas passage, and banks of fluid heating tubes of relatively high heat absorptive capacity positioned in the remaining gas passages.

6. A steam boiler comprising a combustion chamber, an inclined bank of steam generating tubes arranged across the path of the heating gases leaving said combustion chamber, a horizontal steam and water drum positioned a substantial distance above the uppermost point of steam generation in said tube bank, uptake and downtake circulators providing a natural fluid circulation between said drum and tube bank and respectively defining the front and rear walls of the upper portion of said boiler, a partition extending inwardly and upwardly from the rear wall of said boiler and dividing the space above said tube bank and between said circulators into successive upflow and downflow heating gas passages, a steam superheater comprising upper and lower sections located in said upflow gas passage, and a desuperheater receiving superheated steam from said lower superheater section and delivering desuperheated steam to said upper superheater section, and an economizer positioned in said downflow gas passage and discharging into said drum.

7. A steam boiler comprising a combustion chamber, an inclined bank of steam generating tubes arranged across the path of the heating gases leaving said combustion chamber, a steam and water drum positioned a substantial distance above the uppermost point of steam generation in said tube bank, uptake and downtake circulators providing a natural fluid circulation between said drum and tube bank and respectively defining the front and rear walls of the upper portions of said boiler, a partition extending inwardly and upwardly from the rear wall of said boiler and dividing the space above said tube bank and between said circulators into successive upflow and downflow heating gas passages, a bank of steam superheater tubes positioned in the lower portion of said upflow gas passage, and a counterflow economizer comprising a bank of economizer tubes positioned in the upper portion of said upflow gas passage and a second bank of economizer tubes connected to said first bank for a series fluid flow therebetween and positioned in said downflow gas passage with their upper ends connected to said drum.

8. A steam boiler comprising a combustion chamber, a horizontally inclined bank of steam generating tubes arranged across the path of the heating gases leaving said combustion chamber, a steam and water drum positioned above said tube bank, uptake and downtake circulators providing a natural fluid circulation between said drum and tube bank and respectively defining the front and rear walls of the upper portion of said boiler, a partition extending inwardly and upwardly from the rear wall of said boiler and dividing the space above said tube bank and between said circulators into a pair of upflow and downflow heating gas passages of substantial length and arranged in series, fluid heating surface in said upflow and downflow gas passages arranged and proportioned to produce a siphonal heating gas circulation successively through said upflow and downflow gas passages, and suspension means external to said drum for supporting said partition.

9. A steam boiler comprising a combustion

chamber, an inclined bank of steam generating tubes arranged across the path of the heating gases leaving said combustion chamber, uptake and downtake headers connected to opposite ends of said tube bank, a steam and water drum positioned above said tube bank, uptake and downtake circulators connecting said drum to the tops of said uptake and downtake headers respectively, a partition extending inwardly and upwardly from the upper portion of said downtake headers and dividing the space above said tube bank and between said circulators into successive upflow and downflow heating gas passages, a row of partition-supporting tubes extending upwardly from said downtake headers along said partition and having their upper ends connected to said drum, heat transfer surface positioned in said upflow and downflow gas passages, and means protecting the connections between said downtake circulators and downtake headers from the heating gases passing through said downflow gas passage.

10. A steam boiler comprising a combustion chamber, an inclined bank of steam generating tubes arranged across the path of the heating gases leaving said combustion chamber, uptake and downtake headers connected to opposite ends of said tube bank, a steam and water drum positioned a substantial distance above the uppermost point of steam generation in said tube bank, uptake and downtake circulators connecting said drum to the tops of said uptake and downtake headers respectively and defining the front and rear walls of the upper portion of said boiler, a partition extending inwardly and upwardly from the upper portion of said downtake headers and dividing the space above said tube bank and between said circulators into successive upflow and downflow heating gas passages, a row of partition-supporting tubes extending upwardly from said downtake headers along said partition and having their upper ends connected to said drum, a bank of steam superheater tubes positioned in said upflow gas passage between said uptake circulators and said partition-supporting tubes, a bank of economizer tubes positioned in said downflow gas passage between said partition-supporting tubes and said downtake circulators and having their upper ends connected to said drum, and a rearward extension on said partition directing the heating gases leaving said downflow gas passage away from the connections between said downtake circulators and downtake headers.

11. A steam boiler comprising a combustion chamber, a row of fluid cooled ash collecting tubes extending across the upper portion of said combustion chamber, an inclined bank of steam generating tubes arranged across the path of the heating gases leaving said combustion chamber, uptake and downtake headers connected to opposite ends of said tube bank, a steam and water drum positioned a substantial distance above the uppermost point of steam generation in said tube bank, uptake and downtake circulators connecting said drum to the tops of said uptake and downtake headers respectively and defining the front and rear walls of the upper portion of said boiler, a partition extending inwardly and upwardly from the upper portion of said downtake headers and dividing the space above said tube bank and between said circulators into successive upflow and downflow heating gas passages, a row of partition-supporting tubes extending upwardly from said downtake headers along said partition and having their upper ends con-

- nected to said drum, a bank of steam superheater tubes wholly positioned in said upflow gas passage between said uptake circulators and said partition-supporting tubes, a bank of economizer tubes wholly positioned in said downflow gas passage between said partition-supporting tubes and said downtake circulators and having their upper ends connected to said drum, and an explosion door arranged in the roof of said boiler directly above 10 said upflow gas passage.
12. A steam boiler comprising a horizontally inclined bank of steam generating tubes, a steam and water drum positioned above said tube bank, uptake and downtake circulators arranged to provide a natural fluid circulation between said drum and tube bank, a series of supporting tubes having vertical portions positioned above and intermediate said tube bank and between vertical portions of said uptake and downtake circulators and arranged to provide a fluid circulation between said tube bank and said drum, fluid heaters positioned above said tube bank and at opposite sides of said supporting tubes, and means for supporting the adjacent ends of said fluid heaters from said supporting tubes. 20
13. A steam boiler comprising a horizontally inclined bank of steam generating tubes, a steam and water drum positioned above said tube bank, uptake and downtake circulators arranged to provide a natural fluid circulation between said drum and tube bank, a row of supporting tubes having vertical portions positioned above and intermediate said tube bank and between vertical portions of said uptake and downtake circulators and arranged to provide a fluid circulation between said tube bank and said drum, fluid heaters positioned above said tube bank and at opposite sides of said row of supporting tubes, means for supporting the adjacent ends of said fluid heaters from said supporting tubes, and suspension means external to said drum for supporting said supporting tubes. 30
14. A steam boiler comprising a horizontally inclined bank of steam generating tubes, a steam and water drum positioned above said tube bank, rows of uptake and downtake circulators arranged to provide a natural fluid circulation between said drum and tube bank, a row of supporting tubes having vertical portions positioned above and intermediate said tube bank and between vertical portions of said uptake and downtake circulators and arranged to provide a fluid circulation between said tube bank and said drum, fluid heaters consisting of banks of multi-looped return bend tubes positioned above said tube bank and at opposite sides of said row of supporting tubes, means for supporting the adjacent ends of said fluid heaters from said supporting tubes, and suspension means external to said drum for supporting said suspension tubes. 40
15. A steam boiler comprising a horizontally inclined bank of steam generating tubes, a steam and water drum positioned above said tube bank, uptake and downtake circulators arranged to provide a natural fluid circulation between said drum and tube bank, means dividing the space above said tube bank into successive upflow and downflow heating gas passages arranged in series, a row of supporting tubes having vertical portions positioned above and intermediate said tube bank and between vertical portions of said uptake and downtake circulators and arranged to provide a fluid circulation between said tube bank and said drum, fluid heaters positioned in said upflow and 50 downflow gas passages at opposite sides of said
- row of supporting tubes, and means for supporting the adjacent ends of said fluid heaters from said supporting tubes. 5
16. A steam boiler comprising a horizontally inclined bank of steam generating tubes, a steam and water drum positioned above said tube bank, uptake and downtake circulators arranged to provide a natural fluid circulation between said drum and tube bank, means dividing the space above said tube bank into successive upflow and downflow heating gas passages arranged in series, a row of supporting tubes having vertical portions positioned above and intermediate said tube bank and between vertical portions of said uptake and downtake circulators and arranged to provide a fluid circulation between said tube bank and said drum, a fluid heater positioned in said downflow gas passage at a level lower than said drum, and means for supporting the inner end of said fluid heater from said supporting tubes. 10
17. A steam boiler comprising a horizontally inclined bank of steam generating tubes, a steam and water drum positioned above said tube bank, rows of uptake and downtake circulators arranged to provide a natural fluid circulation between said drum and tube bank, means dividing the space above said tube bank into successive upflow and downflow heating gas passages arranged in series, a row of supporting tubes having vertical portions positioned above and intermediate said tube bank and between vertical portions of said uptake and downtake circulators and arranged to provide a fluid circulation between said tube bank and said drum, a fluid heater positioned in one of said gas passages and at a level lower than 15 said drum, means for supporting one end of said fluid heater from said supporting tubes, means for supporting the opposite end of said fluid heater from one of said rows of circulators, and suspension means external to said drum for supporting 20 said supporting tubes. 25
18. A steam generator comprising a setting including a combustion chamber, a horizontally inclined bank of steam generating tubes disposed above said combustion chamber and a substantial distance below the top of said setting, a steam and water drum positioned adjacent to the top of said setting and connected to said tube bank, a row of supporting tubes extending inwardly and upwardly from and connected to one end of said 30 tube bank and having vertical portions positioned above an intermediate portion of said tube bank and connected to said drum, a plurality of separate fluid heaters positioned above said tube bank at opposite sides of said row of supporting tubes, and means for supporting the adjacent ends of said fluid heaters from said row of supporting tubes. 35
19. A steam generator comprising a setting including a combustion chamber, a horizontally inclined bank of steam generating tubes disposed above said combustion chamber and a substantial distance below the top of said setting, a steam and water drum positioned adjacent to the top of said setting and connected to said tube bank, means dividing the space within said setting and directly above said tube bank into successive upflow and downflow heating gas passages arranged 45 in series, said means including a row of supporting tubes extending inwardly and upwardly from one end of said tube bank and having vertical portions positioned above an intermediate portion of said tube bank and connected to said drum, a plurality of separate fluid heaters positioned in said upflow and downflow 50
- 75

- gas passages at opposite sides of said row of supporting tubes, and means for supporting the adjacent ends of said fluid heaters from said row of supporting tubes.
20. A steam generator comprising a setting including a combustion chamber, a horizontally inclined bank of steam generating tubes disposed above said combustion chamber and a substantial distance below the top of said setting, a steam and water drum positioned adjacent to the top of said setting and connected to said tube bank, means dividing the space within said setting and directly above said tube bank into successive upflow and downflow heating gas passages arranged in series, said means including a row of supporting tubes extending inwardly and upwardly from and connected to one end of said tube bank and having vertical portions positioned above an intermediate portion of said tube bank and connected to said drum, a plurality of separate fluid heaters positioned in said upflow and downflow gas passages at opposite sides of said row of supporting tubes, the fluid heater in said upflow gas passage comprising a bank of return bend steam heating tubes, and means for supporting the fluid heaters in said upflow and downflow gas passages from said row of supporting tubes.
21. A steam boiler comprising an inclined bank of steam generating tubes, a steam and water drum positioned above said tube bank, spaced groups of vertically extending uptake and downtake circulators arranged to provide a fluid circulation between said drum and the corresponding ends of said tube bank, a group of suspended supporting tubes having vertically extending portions above said tube bank and between said groups of circulators and having their ends connected for a fluid circulation therethrough, an auxiliary fluid heater positioned above said tube bank and between said groups of circulators, and means for jointly supporting said fluid heater from said supporting tubes and circulators.
22. A steam boiler comprising an inclined bank of steam generating tubes, a steam and water drum positioned above said tube bank, spaced groups of vertically extending uptake and downtake circulators connecting said drum to the corresponding ends of said tube bank, a partition extending transversely of said tube bank and dividing the space above said tube bank and between said groups of uptake and downtake circulators into a pair of heating gas passages, a group of suspended supporting tubes extending upwardly in heat absorbing relation with said partition and having their ends connected for a fluid circulation therethrough, a bank of looped fluid heating tubes positioned in one of said gas passages, and means for supporting said looped tube bank from an adjacent group of circulators and said supporting tubes.
23. A steam boiler comprising an inclined bank of steam generating tubes, a steam and water drum positioned above said tube bank, spaced rows of vertically extending uptake and downtake circulators arranged to provide a fluid circulation between said drum and the correspond-

ing ends of said tube bank, a partition extending transversely of said tube bank and dividing the space above said tube bank and between said rows of circulators into a pair of vertical heating gas passages, a row of tubes having vertical portions supporting said partition and having their ends connected to provide a fluid circulation between said tube bank and said drum, a fluid heater positioned in one of said gas passages, means for supporting one end of said fluid heater from said partition-supporting tubes, means for supporting the opposite end of said fluid heater from one of said rows of circulators, and suspension means external to said drum for supporting said partition-supporting tubes.

24. A steam boiler comprising an inclined bank of steam generating tubes, a steam and water drum positioned above said tube bank, groups of uptake and downtake circulators connecting said drum to the corresponding ends of said tube bank, a partition dividing the space above said tube bank and between said circulator groups into a pair of heating gas passages, a row of suspended fluid heating tubes extending upwardly in heat absorbing and supporting relation with said partition and having their upper ends connected to said drum, a bank of multiple-looped fluid heating tubes positioned in the gas passage adjacent said uptake circulators, means for supporting said looped tube bank from said uptake circulators and partition-supporting tubes, a second bank of multiple-looped fluid heating tubes positioned in the other gas passage, and means for supporting said second looped tube bank from said partition-supporting tubes and downtake circulators.

25. A steam boiler comprising an inclined bank of steam generating tubes, rows of uptake and downtake headers connected to opposite ends of said tube bank, a transverse steam and water drum positioned a substantial distance above said tube bank, vertically extending groups of uptake and downtake circulators connecting said drum to said uptake and downtake headers respectively and providing a fluid circulation between said drum and tube bank, a partition extending transversely of said tube bank and dividing the space above said tube bank and between said groups of circulators into a pair of heating gas passages, a row of partitions-supporting tubes extending upwardly from said downtake headers in heat absorbing relation with said partition and having their upper ends connected to said drum, a bank of multiple-looped fluid heating tubes positioned in the gas passage adjacent said uptake circulators, means for supporting said looped tube bank from said uptake circulators and partition-supporting tubes, a second bank of multiple-looped fluid heating tubes positioned in the other gas passage, means for supporting said second looped tube bank from said partition-supporting tubes and downtake circulators, and suspension means external to said drum for supporting said partition-supporting tubes.
